UNITED STATES PATENT OFFICE.

ITALO ALFRED DE POLO, OF CONNELLSVILLE, PENNSYLVANIA.

SCREENING OR SEPARATING MACHINE.

1,274,014.

Specification of Letters Patent. Patented July 30, 1918.

Application filed August 28, 1917. Serial No. 189,641.

To all whom it may concern:
Be it known that I, ITALO ALFRED DE POLO, a citizen of the United States, residing at Connellsville, in the county of Fayette 5 and State of Pennsylvania, have invented a new and useful Screening or Separating Machine; and I do hereby declare the following to be a full, clear, and exact description of the invention, such as will enable others 10 skilled in the art to which it appertains to make and use the same.

This invention relates to an improved screening or separating machine, for screening or separating ashes, coal and the like, 15 and one of the objects of the invention is to provide an apparatus of this kind having means for digging the ashes or coal or the like from a pile, in combination with means for elevating the same to a rotary screening 20 or separating cylinder.

A further object of the invention is to provide a portable platform or frame, on which an auxiliary frame is pivotally mounted, whereby the auxiliary frame may 25 oscillate, so that the digging means may more conveniently adapt itself for excavating the ashes or the like.

A further object of the invention is the provision of means for oscillating said pivotally mounted auxiliary frame.

A further object of the invention is the provision of means for rotating the screening or separating cylinder and the elevator conveyer.

35 A further object of the invention is the provision of means adapted to be thrown in gear with the screening or separating operating means, whereby the machine (which is mounted upon supporting wheels) may be 40 driven forwardly.

In practical fields the details of construction may necessitate alterations falling within the scope of what is claimed.

The invention comprises further features 45 and combination of parts as hereinafter set forth shown in the drawings and claimed.

In the drawings:-

Figure 1 is a plan view of the improved screening or separating machine, constructed 50 ed in accordance with the invention.

Fig. 2 is a view in side elevation of the same.

Fig. 3 is a cross sectional view on line 3—3 of Fig. 2.

55 Fig. 4 is a sectional view on line 4—4 of Fig. 2.

Referring more especially to the drawing 1 designates a suitable bed frame, which is provided at the rear with a bolster 2 having a rear axle 3, which is provided with supporting wheels 4. The forward part of the bed frame on its under face is provided with a bolster 5, to which an axle bolster 6 is connected in any suitable manner so as to turn, that is, oscillate, whereby the front supporting 60 wheels 7 (which are carried by the front axle 8, which is in turn carried by the axle bolster 6) may be turned in one direction or the other for steering the machine. The usual bars 9 are carried by the axle bolster, 70 and in turn support the tongue 10, to which a team of draft animals may be connected for drawing the machine from one place to another. Swivelly mounted upon the bed frame, by means of the bolt 11 is the base 12 75 of an auxiliary frame 13. By this connection the auxiliary frame 13 may turn or oscillate laterally. This auxiliary frame supports a pair of storage and delivering bins or hoppers 14 and 15, the front and rear 80 sides 16 of each of which are inclined downwardly, as shown. The lateral sides 17 of each hopper are perpendicular and are provided with door openings 18 having doors 19 hinged at 20, there being suitable latches 85 21 to hold the doors closed. The bottom of each hopper comprises the inclined pieces 22, which are inclined downwardly and laterally toward the doors, so that material such as ashes or coal that is screened or separated 90 will easily pass out of the door opening, when the doors are opened. At the rear of the auxiliary frame an elevating conveyer is provided. This conveyer 23 comprises the side members 24 having their upper ends 95 connected by the standards 25 to the upper part of the auxiliary frames 13. The side bars or members 24 are reinforced relative to the standards 26 of the auxiliary frame and its base thereof by means of the braces 100 27 and 28. A suitable digger or scoop member 29 having teeth 30 is provided. This conveyer 23 and the digger or scoop member 29 combined, constitutes a mechanism or means for collecting and delivering material to be graded or separated into a suitable screening or separating means. This digger or scoop member is provided with arms 31, which are forked as shown at 32, said forks being secured at 33 to the lower ends of the 105 side bars or members 24 of said conveyer 23. Mounted in bearings of the upper and lower

ends of the side bars or members 24 are shafts 34 and 35, which have sprockets 36 and 37 about which the chains 38 carrying elevating conveyer buckets 39 travel, where-
5 by ashes, coal or the like, as it is scooped by the digger, may be conveyed upwardly to an improved combined agitator and separator 40. Also mounted in bearings of the side bars or members 24 is a shaft 41 provided
10 with a sprocket 42, about which a sprocket chain 43 travels, which in turn travels about the sprocket 44, which is also carried by the shaft 34. Mounted upon the base of the auxiliary frame is a suitable motor 45, the
15 operating shaft 46 of which has a pulley 47 on one end. A belt passes about the pulley 47, and is consequently designated by the numeral 48. This belt 48 in turn passes about the pulley 49, which is also carried by
20 the shaft 41. Hence when the shaft 46 rotates, power is transmitted to the elevating conveyer, by means of the belt 48, the pulley 49, the sprocket 42 and the chain 43, which operates the sprocket 44. The other
25 end of the shaft 46 is provided with a pulley 50, about which a belt 51 passes. A chute 52 is secured at 53 on the auxiliary frame 13, and a bracket 54 has its arms secured at 56 to the sides of said chute. Formed upon the
30 bracket 54 is a bearing 55, and mounted therein and also in bearing 57 of the standard 58 is a shaft 59, with which an agitator and screening drum 60 rotates. This combined agitator and screening drum 60 is ar-
35 ranged on an incline and directly over the hopper 15, so that the finer parts of the ashes or coal, after passing through the wire fabric of the drum (which fabric may be any suitable mesh) may deposit in the
40 hopper 15, while the larger parts or par-
45 ticles of the ashes or coal may pass into the hopper 14, there being a partition 61 between the two hoppers, to keep the material separated. The elevating conveying buckets as
50 they reach the top of the conveyer dump their contents into the chute 52, hence it passes into the screening drum 60 and as be-
55 fore stated the larger mesh passes into the hopper 14 and the finer mesh into the hop-
50 per 15. Mounted in a bearing of the bracket
62 is a shaft 63 having on one end a pulley
64 and on its other end a bevel gear 65. Mounted in a bearing 66 of the standard 67 on the top of the forward part of the auxil-
55 iary frame is a shaft 68 which is also mount-
ed in the bearing 69 of the standard 58, there
being collars 70 and 71 on said shaft 68 to
prevent axial movement thereof. On one
60 end of the shaft 68 is a pulley 72 and on its
other end a bevel gear 73, which meshes
with the teeth of the bevel gear 74 of the
screening or separating drum. A belt 75
passes about the pulley 64 and about the
pulley 72, so that when motion is imparted
65 to the belt 51 (which passes about the pulley

76 also mounted on the shaft 63) from the motor pulley 50, power is transmitted to the agitator and screening drum, as will be clearly apparent resulting from an examination of the drawings. Mounted in a suitable 70 bearing of the bed frame is a perpendicular shafts 77 having a drum 78 near its lower part and a wheel 79 at its upper end. A cable 80 is passed several times about the drum 78 and has its extremities connected at 81 75 to the base of the auxiliary frame 13, whereby as the hand wheel 79 is manipulated manually in one direction or the other, said auxiliary frame may be oscillated upon its bolt 11, so that the digger or scoop member 80 may accommodate itself more readily to the pile of ashes or coal, whereby the digger may more efficiently scoop or dig them up. Mounted in a bearing 82 of the standard 83 is a shaft 84, on one end of which a sprocket 85 is mounted. A sprocket chain 86 passes about the sprocket 85, and in turn about the sprocket 87 on a stub shaft 88 which projects from one end of the bed frame. Movable 85 with the sprocket 87 is a sprocket 89, and 90 passing about it is a sprocket chain 90, which in turn passes about the sprocket 91, which is rotatable with one of the rear supporting wheels 4 of the bed frame. Splined by 95 means of a feather 92 to one end portion of the shaft 84 is a bevel gear 93. A lever 94 is pivoted at 96 on the standard 97 (which rises upwardly from the bed frame), and has one end provided with forks 95, which have slot and pin connections 98 with the hub 99 of the bevel gear 93, so that by grasping the handle 100 of said lever 94, the bevel gear 93 may be moved axially on the shaft 84 so as to mesh with the bevel gear 65. Since power is transmitted to the gear 65, 105 motion may in turn be imparted to the chain 90 by intermeshing the bevel gears 65 and 93. By this arrangement and operation the apparatus may be moved little by little toward the pile of ashes or coal or the like. The shaft 68 consists of two sections 101 and 102, and their adjacent ends have rectangular portions 103 and 104, with which a suitable sleeve 105 engages. However, the 110 sleeve may be moved axially on the section 101, thereby disconnecting two sections and allowing the section 101 to rotate idly. When so disconnecting the section 101 and removing the belt 48 from the motor pulley 47, the apparatus may be driven from one 115 place to another by means of the chain drive 90 and the intermeshing of the bevel gears 65 and 93. When the two sections 101 and 102 are designed to rotate together, the sleeve 105 may be held to the section 102 by 120 the set bolt 106. In the operation the digger and the elevator which constitute a mechanism for gathering and delivering material to be graded or separated to a combined agitator and separating device, are carried 125 130

upon one end of an auxiliary frame, which is movable to swing about a vertical axis, there being manual means for swinging or oscillating the movable frame for directing the 5 digger to different places or points or a dump. The material when deposited into the combined agitator and separator is agitated and screened into two different grades, which are delivered separably into a pair of 10 storage and delivering bins, which are supported upon and movable with the movable frame.

The invention having been set forth what is claimed as new and useful is:—

- 15 1. In a material handling apparatus, a supporting frame movable to swing about a vertical axis, storage and delivering bins mounted upon and movable with said frame, an agitator and separator mounted upon 20 said frame and adapted to deliver separately graded materials to said bins respectively, means movable with said frame to collect and deliver material to be separated to said agitator and separator, and means mounted 25 upon and movable with said frame to actuate said delivering and separating means.
2. In a material handling apparatus, the

combintion with a wheeled frame, of a second frame movably mounted upon the first frame to swing about a vertical axis, storage and delivering bins mounted upon and movable with the swinging frame, a combined agitator and separator mounted upon said swinging frame and designed to deliver separately graded materials to said 30 bins respectively, the mechanism movable with the swinging frame to gather and deliver material to be separated to said agitator and separator, means mounted upon and movable with the swinging frame to actuate 35 said delivering and separating means, and manually operated means on said wheeled frame and having connections with the swinging frame, whereby said mechanism may gather material from different places of 40 a dump.

In testimony whereof I have signed my name to this specification in the presence of two subscribing witnesses.

ITALO ALFRED DE POLO.
